UNITED STATES PATENT OFFICE

2,164,518

MEANS OF LUBRICATING WAYS

William A. Hart, Detroit, Mich., assignor to Colonial Broach Company, a corporation of Michigan

Application April 13, 1936, Serial No. 74,124

1 Claim. (Cl. 184—6)

The present invention relates to broaching machines and in particular provides an improved system for lubricating the ways which support and guide the broach head of a broaching machine.

Objects of the present invention are to provide an improved means for lubricating the ways which guide a broach head, or like part; to provide such a system which may be economically practised, which are simple and efficient in operation, and which require relatively few operating parts.

Further objects of the present invention are to provide a system for lubricating the ways which guide the broach head of a broaching machine or the like, embodying a cylinder having inlet and outlet passages provided with inlet and outlet check valves, and a piston movable therein in one direction to discharge the lubricant from the chamber through the outlet passage and movable in an opposite direction to establish a partial vacuum therein to draw lubricant into the chamber through the inlet passage; to provide such a system in which the outlet passage is suitably connected to ducts leading to the ways of similar parts to be lubricated; to provide such an arrangement in which the inlet passages may be suitably connected to an oil line otherwise associated with the machine, which oil line is not required to be under more than a limited pressure; and to provide such an arrangement in which, according to one embodiment, the plunger may be actuated automatically in response to the operation of the machine, or in accordance with another embodiment, may be manually actuated.

With the above and other objects in view, which appear in the following description and in the appended claim, preferred but illustrative embodiments of the present invention are shown in the accompanying drawing, throughout the several views of which corresponding reference characters are used to designate corresponding parts and in which:

Figure 1 is a perspective view, with certain of the parts broken away, of a broaching machine embodying the present invention;

Figure 2 is a detailed view in vertical section, taken along the line 2—2 of Figure 1;

Figure 3 is a detailed view in horizontal section, taken along the line 3—3 of Figure 1; and

Figure 4 is a fragmentary view in perspective, showing a modified embodiment of the invention.

Although in its broader aspects the improvements of the present invention are applicable to

various types of machine tools, such improvements are, in a narrower sense, particularly applicable to automatic broaching machines. Accordingly, the drawing illustrates the invention as applied to a broaching machine of the type disclosed in the co-pending application of the present applicant, Serial No. 42,619, filed September 28, 1935, and assigned to the assignee of the present application.

As described in detail in the just identified application and referring to Figure 1, the broaching machine may comprise generally a frame structure 10 formed to provide a horizontally disposed work table 12, and provided with ways 14 formed on the face thereof, which with cooperating dovetail blocks 16, form guideways to guide and support the ram mechanism designated generally as 18. The guide blocks 16 are secured to the face of frame 10 by countersunk studs 20. The broach 22, which may be of generally conventional construction, with a plurality of longitudinally spaced teeth formed on the outer face thereof, is suitably recessed into the forward face of the ram or broach head 18.

In further accordance with the disclosure of the above identified application, the ram mechanism may comprise a frame structure 24, within which a cylinder 26 is secured, which cylinder and frame structure is disposed to reciprocate vertically with respect to a stationary piston (not shown), the piston rod of which is formed of two concentrically disposed pipes 28 and 30. The outer pipe 28 may be suitably ported to afford communication between the space within cylinder 26 above the piston and the interior of pipe 28, and the inner pipe 30 may extend through the piston and communicate with the cylinder space on the other side of the piston. Suitable mechanism, including valves, are provided to selectively connect the pipes 28 and 30 to supply and exhaust lines, respectively, or the reverse, to thereby selectively cause ram mechanism 18 to move upwardly or downwardly, carrying the broach 22 with it to effect the working and return strokes thereof.

The starting, and in certain instances the reversing and stopping of the ram, may be controlled by a manual lever 32, suitably associated with the just mentioned valve mechanism. The intermediate connections between lever 32 and the valve mechanism form no part of the present invention, it being sufficient for the purposes of the present disclosure to note that rotation of lever 32 is effective to initiate the starting, the

reversing, or the stopping, or an associated control function.

Turning now to the elements of the disclosed machine, to which the present invention is specifically directed, a lubricating cylinder 40 is suitably supported, preferably within the machine frame, and is provided with an inlet port 42 and an outlet port 44. A nipple 46, threaded onto inlet 42, is provided with a passage 48 which is adapted to be closed by a conventional flapper type valve 50. A pipe 52, threaded into nipple 46, may extend to any suitable source of lubricant, which may be either a force feed pump conventionally associated with machines of the class to which the present invention relates, or may be tapped into one of the lubricant return lines of such machine.

The outlet passage 44 is adapted to be closed by a ball 54, which is urged to the closed position by a compression spring 56. A nipple 58 connects cylinder 40 to a distribution pipe 60, which may extend upwardly through the machine to the branch pipes 62 and 64 which are threaded respectively in the frame 10 in registry with passages 66 and 68 formed therein. The passages 66 and 68 in turn register with lubricant wells formed in the face of the lubricant wells 70 and 72 formed in the guide blocks 16 and in the guides 14. With this arrangement, it will be evident that lubricant discharged from cylinder 40 through the pipe 60 is supplied to the working faces of the guide blocks 16, the ways 14, and of the ram mechanism 18.

In the form illustrated in Figure 2, cylinder 40 is provided with a piston 80 having an integrally formed shank 82 which extends externally of cylinder 40, and which is biased to the illustrated position by a compression spring 84 which surrounds the shank and is seated between the head 86 thereof and the underside of cylinder 40. Head 86 is formed arcuately for cooperation with a suitable cam 88, keyed to a shaft 90, oscillation of which is effected by the previously described operating lever 32. As will be evident from Figure 2, rotation of lever 32 in a clockwise direction correspondingly rotates cam 88, camming shank 82 and piston 80 upwardly within cylinder 40. The upward movement of piston 80 forces flapper valve 50 to a closed position, closing off the inlet pipe 52, and forces valve 54 to the open position against the force of the spring 56, thus permitting any lubricant collected within cylinder 40 to be forcibly discharged therefrom into the pipe 60, and correspondingly forcibly fed to the wells 70 and 72. Similarly, rotation of lever 32 in a counter-clockwise direction correspondingly rotates cam 88 and permits a return movement of piston 80 under the influence of the compression spring 84. This action permits check valve 54 to close, thus closing off the outlet pipe 60, and by creating a partial vacuum within cylinder 40, permits the opening of flapper valve 50, which action permits oil to flow in cylinder 40 through the inlet pipe 52. Because of the partial vacuum which would otherwise be developed within cylinder 40 by the downward movement of piston 80, it will be evident that a downward movement thereof is always accompanied by the drawing into cylinder 40 of a charge

of lubricant, even though the lubricant in intake pipe 52 may be under only a negligible head. From the foregoing, it will be seen that each oscillation of lever 32 draws a charge of lubricant into cylinder 40 and discharges it under pressure to the ways 14, 16, and the cooperating ways of the ram mechanism 18.

In the alternative embodiment of Figure 4, the pumping structure may be in general as described above, as is indicated by the corresponding reference characters with the subscripts "a". In this instance, however, the cam 88a is formed on a lever 100, pivotally supported upon a shaft 102, and the end 104 of which is disposed in the path of a pin 106, which may be suitably secured to ram 18a for direct movement therewith. Preferably, the mechanism is so positioned that pin 106 engages the end of crank 100 shortly prior to the arrival of the ram mechanism at the upper limit of its stroke. This engagement rotates lever 100 in a counter-clockwise direction, forcing the piston 80a upwardly and discharging lubricant from cylinder 40a to the ram mechanism in the previously described manner. When the ram mechanism 18 starts downwardly, piston 80a is forced downwardly under the influence of the compression spring 84a, associated therewith, which action also forces lever 100 in a clockwise direction to the illustrated position in which it is supported by a stop pin 106. This return movement of piston 80a, as previously described, draws a new charge of lubricant into the cylinder 40a, in readiness for the next upward movement of the piston.

It will be evident from the foregoing that the present invention provides an effective method and means for intermittently supplying lubricant under pressure to the operating parts of a broaching machine or like apparatus. In practice, the disclosed construction substantially eliminates the difficulties heretofore encountered in providing satisfactory lubrication to certain of the parts of such apparatus.

Although specific embodiments of the present invention have been described, it will be evident that various changes in the form, number and arrangement of parts thereof, and various changes in the specific method of practising the invention, may be made within the spirit and scope thereof.

What is claimed is:

In a broaching machine, the combination of a carriage for effecting relative movement between a work piece and a broaching tool; a lubricant pumping device comprising a housing stationarily mounted on said machine and having inlet and outlet ports associated therewith; a piston movable in said housing; a spring for effecting movement of said piston in one direction; a lever pivotally mounted on said machine and having a cam formation thereon against which said piston normally bears and which constitutes a limit to the motion of said piston in one direction; and means carried by said carriage and engageable with said lever to pivot the same and render said cam effective to move said piston within said housing in an opposite direction against the force of said spring.

WILLIAM A. HART.
